STUDIO COUCH

Edward O. Kerr and Joseph J. Rogers, Houston,
Tex.

Application September 17, 1937, Serial No. 164,323

3 Claims. (Cl. 5—18)

This invention relates to new and useful improvements in convertible couches.

One object of the invention is to provide an improved convertible couch of the type generally known and referred to as a studio couch, which may be readily converted into a double bed or two single beds and which is simple in construction, whereby operation is facilitated and manufacturing costs are reduced.

10 An important object of the invention is to provide an improved couch including a main or upholstered section and a movable or secondary section which is normally located beneath the upholstered section and is completely out of the

15 way when the couch is being used as such, there being improved means for lifting the front portion of the main section to permit the lower or secondary section to be readily slid forwardly or outwardly to form the bed, the lifting of said 20 main section in this manner obviating the necessity of providing swinging panels or the like, in the upholstered section, whereby the tailoring of the upholstered section, as well as the general appearance of the same is enhanced.

25 Another object of the invention is to provide a couch of the character described wherein pivot- 30 ed lifting members are mounted on the upholstered section and when swung, are arranged to lift the front portion of said section to permit the lower section to be slid from therebeneath; the lifting members being so constructed that they may be extended and bent so as to form 35 the back of the couch, whereby they become a part of the couch and thereby eliminate unsightly auxiliary levers or handles; the provision of said members also facilitating the conversion of the bed since stooping or bending to raise the comparatively heavy upholstered section is eliminated.

40 Still another object of the invention is to provide an improved mechanism for lifting the upholstered section of a studio couch which is so constructed that after the mechanism has 45 been operated and the couch has been converted into a bed or beds, said mechanism is returned to its normal or original position completely out of the way; there being counterbalancing means associated with the lifting mechanism to facilitate its operation.

A construction designed to carry out the invention will be hereinafter described, together with other features of the invention.

The invention will be more readily understood 55 from a reading of the following specification and

by reference to the accompanying drawings, in which an example of the invention is shown, and wherein:

Figure 1 is a side elevation of a couch, constructed in accordance with the invention, with the lower section in place beneath the upholstered section.

Figure 2 is a side elevation with the forward end of the upholstered section raised and the lower section partially moved from beneath the same.

Figure 3 is a side elevation of the couch converted into a bed, and

Figure 4 is a plan view, with portions broken away to show the relation of the upper and lower sections to each other when moved into position to form a bed.

In the drawings, the letter A designates the upholstered section of a studio couch which section will be hereinafter referred to as the stationary section. This section includes a substantially rectangular frame 10 (Figure 4) which has angular legs or supports 11 at its inside corners. The legs depend vertically from said frame and have their lower ends adapted to rest upon the floor or other support, whereby the frame is spaced from said floor. The frame is completely enclosed on its top and side by upholstering 12 whereby the top of the section A is cushioned in the usual manner. The upholstering covers the upper portions of the legs 11 but has its lower edge terminating a short distance from the lower end of the legs, whereby this lower edge is spaced from the floor. The particular method of upholstering the section A forms no part of the present invention and is therefore, subject to variation.

A movable or lower section B is adapted to fit beneath the stationary or upholstered section A and includes a substantially rectangular, angular frame 13 which is of a smaller size than the frame 10. Depending legs 14 are provided at the corners of the frame 13 and have casters or rollers 15 mounted on their lower ends, whereby movement or sliding of the section B across the floor or other support, is facilitated. A suitable spring structure 16 spans or extends across the frame 13 being fastened in openings 17 provided in said frame. The legs 14 which support the section B, are of less height than the legs 11, which support the upholstered section A; so that when the former section is in position beneath the latter, as shown in Figure 1, the top of the frame 13 is in a plane below the top of the frame 10.

10. Since the frame 13 is smaller in size than the frame 10, it is completely encircled by said frame 10 and is entirely hidden from view by the upholstered sides of the section A.

5. In order to assure the straight outward sliding of the section B from beneath the section A when the front portion of the latter is lifted, and also to prevent binding of the inner frame 13 against the outer frame 10, equalizing bars 18 and 18' are provided. The bars are pivoted to each other at 19 and one end of the bar 18 is pivoted to the frame 10, while the opposite end has a pin 20 which is movable in a slot 21 formed in a longitudinal bar 22 secured to the frame 13. The bar 18' has one end pivoted to the bar 22 while its other end has a pin 23 which is movable in a slot 24 in the frame 10. The equalizing bars assure a straight movement of the section B with relation to the section A and prevent binding thereof. However, said bars are not a part of the present invention and if desired, they may be eliminated.

From the foregoing, it will be seen that the movable or lower section B may be moved beneath the upholstered or stationary section A and the latter will completely cover or enclose the same so as to hide said section B from view. When it is desired to move the section B from beneath the section A so as to convert the couch into a bed, it is necessary that the front portion of the section A be raised or lifted a sufficient distance to allow the section B to clear the front longitudinal bar of the frame 10.

For easily and quickly accomplishing this lifting or raising of the front portion of the section A, an actuating member 25 is provided. This member is shown as an elongate rod which extends longitudinally across the back of the section A and has its ends bent downwardly and forwardly to form a pair of lifting arms or levers 26 (Figure 1). The arms extend contiguous to the sides of the section A and each arm is pivoted near its lower or forward end on a pin 27, which is mounted in the side of the frame 10 of the section A. The longitudinal portion of the actuating member 25 is spaced above the top of the section, so as to form a back rest for the couch and when in such position, the rearward movement of this portion of the member is limited by stop lugs 28 which extend outwardly from the sides of the frame 10. These lugs are engaged by the upper or rear ends of the arms 26. With this arrangement, it is possible to form the back rest and lifting arms of a single rod bent to the proper shape which greatly reduces manufacturing cost, but obviously, the arms 26 could be made separate from the back rest and from each other.

The lower or forward end of each lifting arm or lever has depending ears 29 between which a caster or roller 30 is mounted. A coiled, counterbalancing spring 31 has one end secured to the ears and its opposite end fastened to a pin 32 extending outwardly from the side of the frame and this spring exerts its pressure to constantly urge the forward or lower end of the arm rearwardly of the section A. The disposition of the stop lugs 28 and the distance from the pivot pins 27 to the casters or rollers 30 is such that, when the arms are in a normal inactive position, as shown in Figure 1, there is a slight clearance between the casters 30 and the floor, or other support.

75. The section A has the usual mattress 33 nor-

mally supported thereon and back pillows or cushions 34 are rested against the back formed by the longitudinal portion of the actuating member 25. The lifting arms 26, together with their associate parts, are covered and substantially hidden from view by the usual side framework (not shown) which provides side arm supports on the couch.

When being used as a couch, the parts are in the position shown in Figure 1, with the movable section B completely hidden beneath the upholstered section A. When the couch is to be converted into a bed, the pillows 34 are removed, and the longitudinal portion of the actuating member 25 is swung forwardly of and over the section A. Such swinging of the member 25 swings the forward or lower ends of the lifting arms 26 downwardly and rearwardly, the swinging of said arms being on the pivots 27. This swinging of said arms is aided by the coiled springs 31, and the casters 30 are engaged with the floor. Continued rearward movement of said rollers along the floor causes an upward or lifting movement of the front portion of the section A, as the pivot pins 27 which are attached to the frame 10 are moved upwardly with relation to said floor. The forward swinging of the actuating member 25 and rearward swinging of the outer ends of the arms 26 and rollers 30 is limited by stop pins 35, which extend outwardly from the sides of the frame 10 above the pivot 27. When the actuating member and arms have been swung their full distance, the parts have assumed the position shown in Figure 2, whereby the lower front edge of the upholstered section A has been raised above the top of the section B, to permit the latter to be slid forwardly from therebeneath. The height or distance which the forward portion of the section A is raised depends upon the distance between the pivot pins 27 and the casters, and this distance may be varied as desired.

After the section A is raised, the section B is slid forwardly from beneath the same and the actuating member 25 and arms 26 returned to their normal or original position (Figure 3), whereby the member 25 is again out of the way. The mattress 33 is then placed on the spring structure 16 of the section B and a double bed is formed. To return the section B to its position beneath the section A, the mattress 33 is replaced on the latter section and the actuating member 25 and lifting arms 26 are again swung to raise the front of the section A, whereby the section B can be readily slid therebeneath. It is again pointed out that it is not essential that the arms 26 and the longitudinal portion of the member 25 which forms the back rest of the couch be made integral as the arms could be individually operable. So long as the forward or lower portion of the arms 26 which carry the casters 30 are swung to lift the section A, the purposes of the invention are accomplished and the member or members for swinging said arms are subject to variation.

It is noted that the actuating arms 26 are located exteriorly of the housing so as to be readily accessible. Also since the section A is raised to permit the sliding of the section B, the upholstered section need not be provided with swinging panels or boards to permit the insertion or removal of the section B. The elimination of such panels or boards greatly enhances the appearance of the couch for the upholstering may be finished off more neatly and ragged edges are obviated. It would of course, be possible to move the pivot-

ed pins 27 toward the rear of the section A and lift the rear of the couch by means of the arms 26 in which instance, the section B would be slid outwardly from beneath the rear of said section. 5 However, this latter arrangement would not be as practical as lifting the front of the section A for manifestly, it would necessitate the movement of the upholstered section away from a wall or other obstruction, before the section B could be slid 10 rearwardly from beneath the same.

What we claim and desire to secure by Letters Patent is:

1. A convertible couch including, an upholstered section, a movable section adapted to fit beneath the upholstered section, lifting arms pivotally mounted on the exterior of the upholstered section and adapted to be swung so that their forward ends engage the floor to raise the front portion of said upholstered section, whereby the 15 movable section may be slid outwardly from beneath said upholstered section, and an actuating member connecting the lifting arms so that said arms may be swung simultaneously, said actuating member extending longitudinally of the upholstered section and being spaced above said section to form a back rest.
2. A convertible couch including, an upholstered section, a movable section adapted to fit beneath the upholstered section, lifting arms pivotally mounted on the exterior of the upholstered section and adapted to be swung so that their 20 ends engage the floor to raise said upholstered
3. A convertible couch including, a relatively stationary section arranged to tilt but not to roll on the floor, a rolling section movable under and from the stationary section, lifting arms pivoted to the lower forward portion of the stationary 25 section at their lower end portions and extending above the said section to provide amplified leverage when swung, fulcrum rollers on the lower ends of the arms adjacent the floor and arranged to engage the floor so as to tilt the front portion of said stationary section upwardly to permit said rolling section to be rolled out from beneath the former while the same remains stationary, and an actuating member connecting the upper ends of the lifting arms so that said arms may be 30 swung simultaneously, said actuating member extending longitudinally of the stationary section and being spaced above said section to form a back rest.

section, whereby the movable section may be slid outwardly from beneath said upholstered section, resilient means attached to said arms for urging said arms to their lifting positions, means for limiting the swinging of said arms, and an actuating member connecting the lifting arms so that said arms may be swung simultaneously, said actuating member extending longitudinally of the upholstered section and being spaced above said section to form a back rest.

3. A convertible couch including, a relatively stationary section arranged to tilt but not to roll on the floor, a rolling section movable under and from the stationary section, lifting arms pivoted to the lower forward portion of the stationary 15 section at their lower end portions and extending above the said section to provide amplified leverage when swung, fulcrum rollers on the lower ends of the arms adjacent the floor and arranged to engage the floor so as to tilt the front portion 20 of said stationary section upwardly to permit said rolling section to be rolled out from beneath the former while the same remains stationary, and an actuating member connecting the upper ends of the lifting arms so that said arms may be 25 swung simultaneously, said actuating member extending longitudinally of the stationary section and being spaced above said section to form a back rest.

JOSEPH J. ROGERS. 30
